UNITED STATES PATENT OFFICE.

CHARLES H. ALLEN AND CHARLES J. CALLAHAN, OF ATTLEBORO, MASSACHUSETTS.

NON-SEPARABLE LINK CUFF-BUTTON.

1,078,892.

Specification of Letters Patent. Patented Nov. 18, 1913.

Application filed May 18, 1911. Serial No. 627,961.

To all whom it may concern:

Be it known that we, CHARLES H. ALLEN and CHARLES J. CALLAHAN, citizens of the United States, residing at Attleboro, in the county of Bristol and State of Massachusetts, have jointly invented certain new and useful Improvements in Non-Separable Link Cuff-Buttons, of which the following is a specification.

10 Our invention relates to link cuff-buttons, and it consists essentially in the combination of a pair of button or head members proper, and an interposed connecting link member having its ends bent and pivoted or jointed 15 to the respective head members, all constructed and arranged so that when the device is in the normal or open position, the link or bar member will lie centrally of and at substantially right angles to the heads, 20 longitudinally of the latter, but when in the tilted or closed position the said bent portion will lie materially nearer one end of the head than the other, all as more fully hereinafter set forth and claimed.

25 By means of our improvement, we are enabled to produce a solderless and comparatively inexpensive link cuff-button in which the head members thereof are capable of being tilted or swung inward toward each 30 other 90° from the normally open position, means being provided for holding the heads against movement in a contrary direction.

The invention further resides in arranging and mounting the pintles or pivot portions of the link with relation to the heads so that, when in normal use, the link portion proper will lie centrally of the heads, but the pivots themselves will be eccentric, or non-central to them, thereby permitting the 40 use of materially shorter links as compared with similar heads having centrally pivoted links.

In the accompanying sheet of drawings, Figure 1 represents a front elevation of our 45 improved link cuff-button in the normally open position; Fig. 2 is a corresponding top plan view; Fig. 3 represents the button in the fully closed position; Fig. 4 is a corresponding edge or top plan view; Fig. 5 is a 50 transverse sectional view, in enlarged scale, taken on line 5—5 of Fig. 1; Fig. 6 is a vertical central sectional view, taken on line 6—6 of Fig. 5; Fig. 7 is a similar view, showing the link swung downward, the 55 other head member being omitted; Fig. 8 is a horizontal sectional view, taken on line

8—8 of Fig. 7; Fig. 9 is a similar view, taken on line 9—9 of Fig. 6; Fig. 10 represents a plan view of the link member itself; Fig. 11 is a front elevation of the spring member; Fig. 12 is a view similar to Fig. 3, except that one of the head members is un-tilted; Fig. 13 is a front view showing a slightly modified form of the button. Fig. 14 is a plan view, enlarged, of the corre- 65 sponding link; and Fig. 15 represents an edge view of it.

The following is a more detailed description of our improved link cuff-button and the manner of operation:—

The article as a whole is designated in the drawings by A, which includes the two head members *a* and *b* and the link *n* pivoted to and connecting them. The head members may be alike and have any desired form 70 and ornamentation; we prefer, however, the ellipsoidal shape. Each head consists of the following parts, produced from suitable sheet-metal stock, viz.:—the outer cap or front *c* having an upturned peripheral flange; a substantially flat, resilient disk *e* having, as shown, a T-shaped recess formed therein, adapted to receive an end portion 75 of the link member, and the outer back disk or plate *d*; and having the several members 80 disposed or arranged substantially as shown, and secured together by inturning the cap's flange to form the rounded or beaded edge *c*. The link member *n* is formed from somewhat heavier and different sheet-metal stock than is employed in the said head 85 members. The body part of the link is substantially flat and narrow, its two end portions being bent at substantially right angles. We prefer to have the bent portions 90 disposed so as to face in opposite directions with respect to the plane of the body part of the link, as clearly shown, although both the bent ends may be disposed on one side, as represented in Fig. 15. At or near each 95 terminal of the flat portion of the link is formed a pair of oppositely disposed lateral shoulders *n*³, adapted to engage the back *d*, constituting a stop for limiting the angular movement of the head. The elongated neck 100 or bent portion *n*¹ is somewhat narrower than the said shouldered part and terminates at its free end in the laterally extending trunnion-like members *n*². The width of the slot or opening *d*¹ formed in disk *d* and the 105 registering recessed portion *e*¹ of spring *e* serve as a lateral support for the part *n*¹ of

the link when the members are assembled, the trunnions or pintles n^2 at the same time being movably seated in the corresponding recess e^2 of the spring and retained in place 5 by the superimposed fixed disk d , all as clearly represented in the drawings.

The assembled members composing our improved link cuff-button A appear substantially as shown in Figs. 1, 2, and 13, when in 10 the open or normal position wherein the link n extends horizontally between and connects the two head members a and b , the said connecting member being in the plane of the central or median line $x-x$, the latter being 15 indicated in Figs. 1, 11, and 12. The respective pivot points n^2 on which the heads swing are located below or at a distance from and parallel with said median line. As thus devised, either head when tilted at 20 right angles, as indicated in Fig. 12, may be readily inserted endwise through both the two registering end buttonholes of a cuff and then swung back to its open or normal position, the spring e meanwhile yielding 25 sufficiently during the operation. Since either head is capable of being swung or tilted on its pivot, the insertion may be effected from the right or left, at will. If desired, both heads may be tilted or folded 30 so as to lie flatwise and parallel, as shown in Figs. 3 and 4. By thus hinging the link to the heads at points quite a distance from the central line $x-x$, the link may be made materially shorter than if it were centrally 35 pivoted to the heads, thereby, when in use, correspondingly reducing the lateral space or opening lying between the outer ends of the cuff.

While we have represented the body portion 40 of the link as being comparatively narrow, thereby permitting it to be turned in

the buttonholes of the cuff, we do not desire to confine ourselves to a link having the narrow body-portion, which, while it has the advantage of permitting the link to be 45 turned in the button holes of the cuff is not essential to the perfect operation of the button.

Having thus described our invention, what we claim and desire to secure by U. S. Letters Patent is:—

In a link cuff button, a pair of button heads each comprising a back plate, a dished cap or front plate having an inwardly flanged edge serving as securing means for 55 the back plate, and an oval-shaped resilient disk mounted within the cap plate in back of the back plate, said disk having a T-shaped recess and the back-plate having a slot registering with said recess and disposed 60 at right angles to the head of the recess, both the slot and the recess being eccentric to the center of the button head, a link having T-shaped ends disposed to project in opposite directions with respect to the plane of the 65 body of the link, said T-shaped ends of the link extending through the slots in the back plates and lying within the recesses in the resilient disks and shoulders at the ends of the body portion of the link which engage 70 the back plates of the button heads and act as stops for limiting the movement of the latter, the link having a curved edge to reduce the width of the link intermediate its 75 ends.

In testimony whereof we have affixed our signatures in presence of two witnesses.

CHARLES H. ALLEN.

CHARLES J. CALLAHAN.
